UNITED STATES PATENT OFFICE.

JOHN S. JACQUES, OF HINGHAM, MASSACHUSETTS.

PNEUMATIC-DESPATCH-TUBE APPARATUS.

1,172,598.

Specification of Letters Patent. Patented Feb. 22, 1916.

Application filed September 25, 1909, Serial No. 519,516. Renewed July 8, 1915. Serial No. 38,776.

To all whom it may concern:

Be it known that I, JOHN S. JACQUES, a citizen of the United States, residing at Hingham, in the county of Plymouth and 5 State of Massachusetts, have invented new and useful Improvements in Pneumatic-Despatch-Tube Apparatus, (Case B,) of which the following is a specification.

This invention relates to improvements in 10 pneumatic despatch tube apparatus and the object is to provide a novel means of automatic electric control of the air current, whereby the carrier, in entering the transmission tube, starts the air current creating 15 means into operation, and in leaving the tube discontinues the operation of the current creating means.

In the attainment of this object, I have 20 provided a single electric circuit connecting two terminals of one tube, a normally open switch in said circuit at one station, a normally closed switch at the second station in said circuit, an electro-magnet in said circuit at the first station and an armature 25 operatively connected to the normally open switch and arranged to coöperate with said electro-magnet, whereby, when the normally open switch is closed, a circuit is completed to the electro-magnet, thereby energizing the same to attract the armature 30 and thereby hold the normally open switch closed, and when the normally closed switch is opened the electro-magnet is deenergized and the normally closed switch is released 35 and allowed to open. The air current creating means is suitably actuated by the making and breaking of the circuit so as to be in operation only during the passage of a carrier through one of the transmission 40 tubes. Preferably the operation of the switches is automatically controlled by the passage of a carrier through the transmission tube.

The invention consists in the novel features of construction and in the combination and arrangement of parts set forth in the following specification and particularly pointed out in the appended claims.

Referring to the drawings: Figure 1 is 50 a diagrammatic view showing one of the transmission tubes connecting two terminals at two stations which will be referred to as "Station A" and "Station B," and showing also the air current creating means and 55 its connection with the terminal at station A. Fig. 2 is a diagrammatic view showing

a second transmission tube connecting two other terminals located at station A and station B, respectively, and showing also the pipe connection which leads from the terminal at station A to the air current creating means. Fig. 3 is a diagram showing a part of the electric connections between the two stations. Fig. 4 is a diagram showing the remainder of the electrical connections between the two stations and the electric motor for driving the air pump. Fig. 5 is a detail elevation of one of the terminals at station B. Fig. 6 is an elevation viewed from the right of Fig. 5. Fig. 7 is a detail elevation 70 of one of the terminals at station A. Fig. 8 is a plan section of a portion of one of the terminals at station A. Fig. 9 is a front elevation of the terminal shown in Fig. 8. Fig. 10 is a detail plan of one of the 75 switches shown in Fig. 8, showing the rotatable drum of said switch in another position. Fig. 11 is a detail elevation of the second terminal at station B. Fig. 12 is an elevation viewed from the left of Fig. 11. 80

Like reference characters refer to like parts throughout the several views of the drawings.

In the drawings, referring to Figs. 1 and 2, 15 is a transmission tube connecting two terminals 16 and 17 located at two stations A and B, respectively, and 18 is a second transmission tube connecting two terminals 19 and 20 located at said stations, respectively. The terminal 16 is connected by 90 piping 21 to the outlet of an air current creating device 22 which, preferably, consists of an air pump, and the terminal 19 is connected to the inlet of said air pump by piping 23. When the air pump 22 is driven in the proper direction by an electric motor 24, a current of air is created in the transmission tube 15 in the direction of the arrows *x* and at the same time an air current is created in the transmission tube 18 in the 100 direction of the arrows *y*.

In order that the apparatus shall operate with the maximum of economy, it is desirable that the air current creating means shall be in operation only during such time as a carrier is being transmitted through one of the transmission tubes. To that end, I have provided certain novel electrical means for automatically controlling the operation of the air current creating means 105 by the passage of the carriers through the transmission tubes, so that when a carrier 110

enters one of the transmission tubes, the air current creating means is started into operation and when said carrier passes outwardly from said tube the operation of the air current creating means is discontinued.

I will now proceed to describe the electrical devices by which this result is accomplished. Referring now to Figs. 3 and 4, 25 is an electric switch located at station A and connected in an electric circuit 26 to a switch 27 located at station B, the switch 25 being normally open, and the switch 27 being normally closed. An electro-magnet 28 is connected in series with the circuit 26, so that when the switch is closed the circuit is completed and said electro-magnet is energized thereby, and when the normally closed switch 27 is opened, the circuit is broken and the electro-magnet becomes deenergized. 10 The switches 25 and 27 in the circuit 26 are controlled by the passage of a carrier through the transmission tube 15 in a manner which will be hereinafter fully described. A normally open switch 29 is located at station B and is connected in a circuit 30 with a normally closed switch 31 located at station A. An electro-magnet 32 is connected in series with the circuit 30, so that when the normally open switch 29 15 is closed said electro-magnet is energized thereby and when the normally closed switch 31 is opened said electro-magnet becomes deenergized. The switches 29 and 31 and circuit 30 are controlled by the passage 20 of carriers through the transmission tube 18 in a manner which will be fully described hereinafter.

Referring now to Figs. 8 and 9, the switch 25 is preferably of the rotary type and comprises a drum 33 formed of insulating material having on its periphery a segmental contact plate 34 adapted to contact with two suitable brushes 35 and 36 connected in the circuit 26. The drum 33 is secured to a 25 rock-shaft 37 journaled in suitable bearings in the terminal 16 and having secured thereto an arm 38 located within said terminal and normally extending into the path of the carriers. The drum 33 and arm 38 are normally held in the position shown in Fig. 9 30 by any suitable means, such, for example, as a weight 39 secured to an arm 40 fastened to the rock-shaft 37. Thus, it will be seen that the contact plate 34 of the switch 25 is normally out of contact with the brushes 35 and 36.

Referring now to Figs. 11 and 12, the switch 27 of the terminal 17 is preferably of the rotary type and comprises a drum 41 formed of insulating material having on its periphery a segmental contact plate 42 which is normally in contact with two suitable brushes 43 and 44 connected in the circuit 26. The drum 41 is secured to a rock-shaft 45 35 journaled in suitable bearings on the ter-

rninal 17, and secured to this rock-shaft is a cover 46 which normally closes a carrier outlet 47 of the terminal 17, said cover being normally held in its closed position by any suitable means, such, for example, as a weight 48 secured thereto. The cover 46 is normally locked in this closed position by a suitable latch 49 pivoted at 50 and having thereon a cam 51 which normally projects into the path of the carriers, so that a carrier, in passing outwardly through the outlet 47, engages said cam and moves the latch 49 out of engagement with the cover 46 against the tension of a spring 52. In this way the cover 46 is released and allowed to be opened by the impact of the carrier striking the upper side thereof. After the carrier has passed out, the weight 48 acts to return the cover 46 to its normal position.

Referring now to Fig. 1, the terminal 16 is provided with a carrier inlet 53, normally closed by a cover 54, which cover is moved into its closed position by suitable means, such as a spring 55, and locked in such position by means of a suitable latch 56. 90 When the operator at station A opens the cover 54 and inserts a carrier in the terminal 16, said carrier falls and strikes the arm 38, thereby rocking the shaft 37 and actuating the switch 25 to close the circuit 26, 95 thereby energizing the electro-magnet 28. The carrier, in moving the arm 38 downwardly, causes the arm 40 to be moved from the vertical position shown in Fig. 9 to a horizontal position, and the arm 40 is held 100 in the latter position by an armature 57 formed on, or fast to, the arm 40, said armature being attracted and held by the electro-magnet 28 while said electro-magnet is energized. Thus it will be understood that when the carrier enters the transmission tube 15 at the terminal 16 it actuates the switch 25 to close the circuit 26, and when said carrier passes outwardly through the outlet 47 said carrier actuates the switch 27 110 to break said circuit.

The terminal 17 is provided with a branch 58 having an outlet orifice 59 open to the atmosphere at all times for the escape of the air under pressure in the transmission tube 15 during the passage of a carrier therethrough, said branch being preferably turned upwardly to prevent the air current from blowing upon the counter at station B.

I will now proceed to describe the means by which the electric motor 24 which drives the pump 22 is started into operation when the carrier is introduced into the transmission tube 15 and stopped when a carrier passes out from said transmission tube. A 125 switch 60 is located at station A. Another switch 61 is located at station B, these switches being connected in parallel with suitable circuit wires 62 to the electric motor 24. The switch 60, which is shown in 130

detail in Fig. 10, is preferably of the rotary type and comprises a drum 63 formed of insulating material having secured to its periphery a contact plate 64 adapted to contact with three brushes 65, 66 and 67. The brush 66 is connected to the circuit wiring 62 by a suitable resistance 68, and the brushes 65, 66 and 67 are so arranged that during the first part of the movement of the drum 63, the brushes 66 and 67 contact with the contact plate 64, thereby completing a circuit from a suitable source of current to the motor 24 and throwing the resistance 68 into circuit, continued movement of the drum resulting in the resistance being cut out of circuit, and the full current being delivered to the motor by reason of the fact that the brush 66 passes out of contact with the contact plate 64 when the brush 65 passes into contact therewith, as clearly shown in Fig. 10.

The drum 63 is secured to the rock-shaft 37 so as to be actuated thereby when a carrier strikes the arm 38, and it will be evident that during the passage of a carrier through the transmission tube 15 the electro-magnet 28 will act to hold the switch 60 closed so as to continue the operation of the motor 24. When the carrier passes outwardly through the outlet 47, said carrier actuates the switch 27, as hereinafter described, to break the circuit 26, thereby causing the electro-magnet 28 to be deenergized, thus releasing the armature 57 and allowing the rock-shaft 37 to return to its normal position and consequently returning the switch 60 to its normal position, thus breaking the circuit 62, whereupon the motor 24 stops.

Referring now to Figs. 5 and 6, the switch 29 is preferably of the rotary type and comprises a drum 69 formed of insulating material having secured to its periphery a segmental contact plate 70 adapted to contact with two suitable brushes 71 and 72 connected in the circuit 30. The drum 69 is secured to a rock-shaft 73 journaled in suitable bearings in the terminal 20, said rock-shaft having secured thereto an arm 74 projecting into the path of carriers in said terminal, and being so arranged that when a carrier strikes the arm 74 the contact plate 70 is moved into contact with the brushes 71 and 72 and the circuit 30 is completed thereby.

Secured to the rock-shaft 73 is a lever 75 having thereon a weight 76 which acts to normally hold the drum 69 and arm 74 in the position shown in Fig. 5. Formed on, or secured to the lever 75, is an armature 77 which is adapted to be moved by said lever into contact with the core of the electro-magnet 32 upon the completion of the circuit 30 by the switch 29.

The switch 31 is preferably of the rotary

type and comprises a drum 78 formed of insulating material having secured to its periphery a segmental contact plate 79 which is normally in contact with two brushes 80 and 81 connected in the circuit 30. The drum 78 is secured to a rock-shaft 82 journaled in suitable bearings on the terminal 19, said rock-shaft having also secured thereto a cover 83 which normally closes a carrier outlet 84. The cover 83 is moved into its closed position by any suitable means, such, for example, as a weight 85 mounted thereon, and is locked in such position by means of a latch 86 pivoted at 87. The latch 86 has formed thereon, or secured thereto, a cam 88 which normally projects into the path of carriers in the terminal 19, so that a carrier, in passing outwardly through the outlet 84, strikes said cam and moves the latch 86 out of engagement with the cover 83 against the tension of a spring 89, thereby allowing said cover to be opened by the impact of a carrier striking the upper side thereof. Thus, it will be seen that as the carrier passes outwardly through the outlet 84, the switch 31 is actuated, breaking the circuit 30, thereby deenergizing the electro-magnet 32 and allowing the armature 77 to return to its normal position.

The switch 61 is identical in construction and operation with the switch 60 and therefore a detailed description of the same will be unnecessary, it being understood that said switch is operated to complete the motor circuit when a carrier is introduced into the terminal 20 and during the passage of said carrier through the transmission tube 18 said switch is held in its closed position by means of the armature 77 coöperating with the electro-magnet 32. When the carrier passes outwardly through the outlet 84, said carrier actuates the switch 31, as hereinbefore described, to break the circuit 30, thereby deenergizing the electro-magnet 32, thereby releasing the armature 77 and allowing the switch 60 to return to its normal position, thereby breaking the motor circuit, whereupon the motor 24 stops.

The general operation of the despatch tube apparatus hereinbefore described is as follows: The operator at station A introduces a carrier of well known construction into the terminal 16 and said carrier actuates the switch 60, as hereinbefore described, to start the air pump 22 into operation, thus creating an air current from the terminal 16 to the terminal 17 and outwardly through the orifice 59 to the atmosphere, said current forcing said carrier through the tube 15 to the terminal 17 and outwardly through its outlet 46, whereupon the carrier actuates the switch 27 to break the motor circuit, thereby stopping the operation of the pump 22. The operator at station B, after making the

change, introduces the carrier into the terminal 20 and said carrier actuates the switch 61, as hereinbefore described, to complete the motor circuit, thereby starting the air pump 22 into operation, thus creating an air current from the terminal 20 through the tube 18 to the terminal 19 and moving the carrier from the former terminal to the latter terminal and outwardly through its outlet 84, said carrier actuating the switch 31, as hereinbefore described, to break the motor circuit, whereupon the operation of the pump 22 is discontinued.

Having thus described my invention, what I claim and desire by Letters Patent to secure is:

1. A pneumatic despatch tube apparatus having, in combination, two tubes connecting two stations and through which carriers are adapted to be transmitted, an air current creating device having an inlet connected to one of said tubes and an outlet connected to the other of said tubes, a switch located adjacent to the outlet end of each of said tubes, a shaft rotatably mounted adjacent to the receiving end of each of said tubes, a pair of switches mounted on said shafts, one of said switches being connected in circuit with the switch at the outlet end of its respective tube, the other of said switches being connected in circuit with said air current creating device, means on said shafts adapted to be actuated by the passage of carriers through said tubes to rotate said shafts and close the switches mounted thereon, means on said shafts adapted to hold said last named switches in said closed condition while the electric circuits including the switches at the opposite ends of said tubes are energized, and means adapted to return said switches to their normal positions upon the deenergizing of said last named circuit.

dition while the electric circuits including the switches at opposite ends of said tubes respectively are energized.

2. A pneumatic despatch tube apparatus having, in combination, two tubes connecting two stations and through which carriers are adapted to be transmitted, an air current creating device having an inlet connected to one of said tubes and an outlet connected to the other of said tubes, a switch arranged at the outlet end of each of said tubes, a shaft rotatably mounted adjacent to the receiving end of each of said tubes, a pair of normally open switches mounted on each of said rotary shafts, one of said switches being connected in circuit with the switch at the outlet end of its respective tube, the other of said switches being connected in circuit with said air current creating device, means on said shafts adapted to be actuated by the passage of carriers through said tubes to rotate said shafts and close the switches mounted thereon, means on said shafts adapted to hold said last named switches in said closed condition while the electric circuits including the switches at the opposite ends of said tubes are energized, and means adapted to return said switches to their normal positions upon the deenergizing of said last named circuit.

In testimony whereof I have hereunto set my hand in presence of two subscribing witnesses.

JOHN S. JACQUES.
